UNITED STATES PATENT OFFICE.

FRANK PARIZEK, OF CHICAGO, ILLINOIS.

HINGE.

1,115,450.

Specification of Letters Patent. Patented Oct. 27, 1914.

Application filed February 20, 1913. Serial No. 749,621.

To all whom it may concern:

Be it known that I, FRANK PARIZEK, a citizen of the United States, residing at Chicago, in the county of Cook and State of Illinois, have invented a certain new and useful Improvement in Hinges, of which the following is a full, clear, concise, and exact description, reference being had to the accompanying drawings, forming a part 10 of this specification.

My invention relates to hinge mechanism and is more particularly of value in connection with devices such as doors or windows which it is desired to hold in various 15 different angular positions.

My invention is of particular utility in connection with window shields of automobiles, for instance, or in connection with the front windows of limousine cars or similar 20 inclosures which at various times it is desired to hold at different angular positions.

Without limiting my invention, I will describe it herein in connection more particularly with the front window of a closed vehicle, referring in this description to the accompanying drawing illustrating the same 25 in which—

Figure 1 is a partial front view of a tiltable window mounted by means of my improved bracket; Fig. 2 is a side view thereof showing the window in an alternative position in dotted lines; Fig. 3 is a sectional view of my improved hinge mechanism; Fig. 4 is a detail front view of a portion of 35 the hinge, and Fig. 5 is a detail side view of one of the movable elements of the device.

Referring more specifically to Figs. 1 and 2, I show a window casing 1 within which a tiltable window frame 2 having the pane 3 is adapted to be mounted, by means of my improved hinge mechanism 4 of which I preferably desire to have one at each of the opposite sides. By means of my improved hinge mechanism the window 3 may be held 45 in any one of a great plurality of different angular positions, one of which is shown in dotted lines in Fig. 2.

My improved hinge mechanism is more clearly shown in Figs. 3, 4 and 5 in which 50 the mechanism comprises a rear plate 6 having the projecting arm 7 for mounting purposes. This plate 6 has an inclined conical surface 7^a and has an inner annular depression within which a plate 8 having 55 apertures 9, 9 is fixedly mounted. A stud 10 also forms part of this plate 6 and pro-

jects forwardly therefrom, being screw threaded as more clearly shown in Fig. 3. The apertures 9 are designed to serve as resting positions for balls 11, 11 of which 60 there are preferably 4, which balls are carried upon a second disk 12, which second disk has an overhanging annular portion 13 having a conical interior surface and adapted to engage the conical surface 7^a. The 65 balls 12 are movably mounted within cylinders 14 securely held within the disk 12. Springs 15 are pressed against the balls and hold them downwardly, pressing them into the recesses 11 when the cover plate 16 is 70 mounted in place, being held by two screws passing into the screw threaded holes 17, 17. The heads of these screws 17 hold the plate 16 in shape although they are not shown in Fig. 3 for the sake of clearness. A heavy 75 spring 18 rests upon the plate 12 and is held in place by means of the nut 19 screwed to the stud 10. It will thus be seen that while the spring 18 tends to push the inclined annular surfaces of the elements 6 80 and 12 together at the surface 7^a, and thus to hold the parts tightly together, the pressure of the springs 15 against the balls 11 tends to counteract in a measure this pressure more especially during the time that 85 the balls are moving from one aperture 9 to the other, at which time of course the parts 6 and 12 have relative angular movement, and it is at that time wise to reduce the friction at the surface 7^a. The plate 12 90 carries wings 20, 20 by means of which it is fastened to the window frame 2. It will be readily seen that as the window is rotated the balls find lodgment within a recess 9 and on account of the springs 15 hold the 95 window in the position in which it is placed. The springs of course, are strong enough to withstand wind pressure.

By means of the construction which I have described I am enabled to secure a 100 mechanism which maintains its alignment and holds the parts in proper tight-fitting condition irrespective of the rattling and vibrating motion to which the parts are subjected under conditions of the ordinary automobile use. One of the features which tends to this result is the use of the inclined surfaces between the elements 6 and 12. It will be noted that the stud 10 is of less diameter than the opening through the part 110 105 110 so that this plate does not have frictional engagement with this stud, the frictional

contact being at the surface 7. I find that by means of this particular structure the window is accurately held in a position in which it is placed and may occupy a closed position without rattling and without being shifted by the wind.

Having thus described one form which my invention may take, it will be apparent that many modifications may be made without departing from its spirit.

While I have however described the specific embodiment shown, what I claim as new and desire to secure by Letters Patent is:

15 A device of the character described comprising two relatively rotatable elements, said elements having surfaces inclined to their axis at their engaging peripheries, means for resiliently holding said elements 20 in engagement, means interposed between

said elements to hold them in any one of a plurality of given predetermined positions, said means including a plurality of spring pressed elements having rounded engaging surfaces mounted upon one of said elements, 25 a plurality of recesses to receive said rounded elements provided upon the other relatively rotatable element, said last aforesaid springs opposing the action of said resilient means aforesaid, and a cover plate 30 for engaging said springs to exert pressure against said spring pressed elements.

In witness whereof I hereunto subscribe my name this 31st day of January, A. D., 1913.

FRANK PARIZEK.
